(57) **CLAIM**

The ornamental design for a press brake machine, as shown and described.

DESCRIPTION

FIG. 1 is a front view of a press brake machine showing our new design.

FIG. 2 is a right side view thereof;

FIG. 3 is a left side view thereof;

FIG. 4 is a front and right side perspective view thereof; and,

FIG. 5 is a front and left side perspective view thereof. The broken lines show portions of a press brake machine which form no part of the claimed design.
